Richard Hayes
Yard's Patent

The defendant refers to his last Letters Patent and making part of the same containing a description in the words of the said Richard Hayes himself of his improvement in the machine for Drawing or Ironing clothes.

To all to whom these presents shall come. Be it known that I Richard Hayes of the Town of Pittsfield in the County of Berkshire and State of Virginia have invented a new and useful machine for Drawing Steel Quills ~~Machine~~ and that the following is a full and exact description of the construction and operation of the said machine as invented by me. The machine should be constructed of wrought iron. The principle part is the frame formed by bending the bars in the middle at right angles, making two parallel legs open at the bottom. This upright frame has attached to its sides two drawing bars with thick iron heads and troughs. At the top or Tongue with its drawing bars are two holes for the ends of the frame. The frame - the pair of parallel legs from the bottom are connected at the top at right angles (the top being the middle part of the bars from which goes the whole frame) The top of the frame is enlarged and poised for the ends of the drawing bars, which enlargement is supposed to receive the first bar of the drawing bars - the latter to enter the said bars central. Diagonally on the upper end on either part of each leg are placed on each side in which to hold the stages in drawing bars. From the ends on the outside on the middle of each leg is projecting out at right angles with the leg of iron rods and bars to be poised for the stages of the side bars. The bottom of each leg is turned out at right angles according with the side of the said and poised with a screw hole, for the lower part of the side bars to work in. Each leg is provided with a hole from the bottom to the top on the inside for the insertion of the drawing bars to slide into. The stages may be simply iron blocks at one end and poised at the other. The side bars. The two bars of wrought iron fastened to the frame have a narrow slot to fit the holes in the bottom of each leg. A iron bar of iron is fastened like a large circular bolt head, on the outside of each as a pointed spur. These upper holes are placed on the edge of the bars smaller than those lower holes.

on the plain part near the middle they are perforated for the reception of a broad bar, when necessary. They are rounded hollow and light up through the feet and run alongside the frame to set a bar longer than the former. If the base is broad and the frame of sufficient length these screws may be dispensed with. The drawing screws, also of two kinds. The first is a bolt of sufficient length cut with a thread at its extremity, the lower extremity is formed with two eyes in each of which hangs a single link, above and near the eyes and at right angles with them are projections sufficiently long to enter and slide in the side grooves of the frame when the screw is in its place through the top. This screw is for drawing plain bolts, spikes, &c. The second is similar to the first except that instead of eyes and links at the lower extremity, it is three broad form, and the projections to slide in the side grooves are placed in the direction of the bolt. This screw is for drawing ring or eye bolts. The projections on these bolts made to fit in the side grooves are necessary to keep the bolt in position while operating and thus insures it from any unusual strain. The nut heads, also of two kinds. The first is a nut of the proper size to fit the drawing screws, and made with lever arms of sufficient length to give the required power. This nut when of sufficient size will fit into the eye on the top of the frame. The second is a nut made also to fit either drawing screw and the eye on top of the frame, but instead of arms it is perforated like the barrel head of a carb or a piston for the reception of force bars. This nut is to be used when the situation of the object to be drawn precludes the application of the first as in a corner, near the side, floor, &c. The force bars being the strongest instrument shaped something like a blacksmith's tong the jaws are concave within to receive the head of the bolt spike, &c. The lips are slightly hollow and serve out to grip firmly the bolt spike, &c. The upper ends of the shanks are turned out to form hooks. At a convenient distance below these hooks, the shanks are enlarged and pointed in the direction of the holes being for the reception of the drawing bolt. The drawing bolt is of a proportionate size to the tongs and of sufficient length to be driven down over the hook to turn the tongs on the head of the bolt, spike, &c. and thereby hold a grip provided it be otherwise assisted by a projecting iron enlarger head. The drawing bolt has a nut on each end to screw up on the tongs to draw them. The application of the object to be drawn to a place or in a level with the surface of earth by means

Wants one of sufficient wood around to admit the nose of the tong. The tong are applied to the head of the bolt. While in a line with its direction and the nut on the closing bolt screwed tightly together. Should the object be of the size of an enlarged head then handle the arms of the closing bolt and thereby turn the tong on the bolt to in the same manner as if it was a screw plate by which a head will be out-sufficient to hold firm. The tong being adjusted at the frame over it so that the tong extend up between its legs. If the base is irregularly giving out the frame from otherwise standing in a line with the tong and object to be drawn adjust the side screws to regulate the legs so that the object is accomplished. Then if necessary hook in the right leg and fasten them so as to steady the machine. The drawing down is now done a sufficient speed so as to admit of placing the links at its lower end under the heads of the tong, (the projections being gradually in the side groove) when done work up on the nut head and the object must necessarily be drawn in a right line. If the object to be drawn is longer than the frame length of leg, the side screws. Should the object to be drawn be an eye or ring bolt, substitute the block drawing bolt and dispense with the scope. Hook the lower end with the eye or ring and operate as before.
